UNITED STATES PATENT OFFICE.

JOSEPH H. MONAHAN, OF WORCESTER, MASSACHUSETTS.

BELT ATTACHMENT.

Application filed May 11, 1927. Serial No. 190,588.

This invention relates to a device or attachment designed to be placed on the waist belt of the wearer and to provide a convenient support for a bunch of keys or other similar articles.

It is the general object of my invention to provide an attachment by which the keys or other articles will be securely held, but but from which they may be quickly and 10 easily detached when desired.

A further object is to provide such an attachment which may be cheaply and easily manufactured and which may be formed largely by punching or pressing operations.

15 My invention further relates to arrangements and combinations of parts which will be hereinafter described and more particularly pointed out in the appended claims.

A preferred form of the invention is shown 20 in the drawings in which

Fig. 1 is a front elevation of my improved attachment as mounted for use;

Fig. 2 is a side elevation of the device;

25 Fig. 3 is a front elevation of the supporting member;

Fig. 4 is a rear elevation of the tongue;

Fig. 5 is a sectional side elevation of the device, taken along the line 5—5 in Fig. 1;

30 Fig. 6 is a transverse sectional view, taken along the line 6—6 in Fig. 1; and

Fig. 7 is a detail sectional view, taken along the line 7—7 in Fig. 2.

Referring to the drawings, my improved 35 belt attachment comprises a supporting member 10, and a tongue member 11 mounted for swinging movement on said supporting member.

The supporting member is preferably 40 formed from a single piece of sheet metal, which is bent and pressed to provide a hook portion 12, a loop portion 13, and a bearing portion 14 (Fig. 5) for the tongue 11. The hook 12 is substantially rigid and is preferably of the grooved or arched cross section indicated at 15 in Fig. 7, by which section the stiffness of the hook is substantially increased.

The opposite end of the member 10 is bent 50 around in partially cylindrical shape to provide a bearing portion 14 for the tongue member 11, and is then bent to provide the substantially rectangular loop portion 13 through which the belt of the wearer may be inserted. The extreme inner end 16 of the 55 loop portion 13 is provided with a projection 17 extending through a recess 18 in the

member 10 and preferably headed over to prevent displacement thereof. The end wall 19 of the loop 13 is also provided with an opening 20 for a purpose to be described. 60

The tongue 11 is provided with a partially cylindrical bearing portion 22 (Figs. 4 and 5) at one end thereof, adapted to fit loosely around the bearing portion 14 of the member 10. At the extreme inner end of the portion 22 of the hook a lug or projection 24 is provided, adapted to be inserted in the opening 20 in the wall 19 of the loop 13.

The tongue member 11 is so shaped that the tongue will be held under tension against 70 the upper end of the hook 12 when the bearing portion 22 of the tongue encircles the bearing portion 14 of the supporting member and the lug 24 is inserted in the opening 20.

75 My improved belt attachment thus comprises only two operative members, each adapted to be formed from sheet metal by simple punching or pressing operations and so associated that no wear or breakage of the 80 parts is at all probable.

To improve the appearance of the article, I may insert a sleeve 26 in the portion 14 of the supporting member 10, after the parts are assembled, and I then insert headed 85 studs 27 in the ends of said sleeve to cover the bearing portions of the hook and supporting member, and to provide an ornamental finish for this portion of the attachment.

Having described the construction of my 90 improved belt attachment, the use and advantages thereof will be readily apparent. The tongue member 11 is made of material which is sufficiently resilient to keep it pressed yieldingly upward against the end of the hook 12, but the entire length of the tongue 11 forms a single yielding member, so that the parts may be readily separated by pressing the hook downward when it is desired to remove an article from the attachment. At the same time, there are no 100 loose or separate small springs to be displaced or to become broken in use.

Having thus described my invention and the advantages thereof, I do not wish to be limited to the details herein disclosed, otherwise than as set forth in the claims, but what I claim is:—

1. A belt attachment comprising a supporting member and a tongue mounted for 110 swinging movement thereon, said tongue and supporting member having curved portions

substantially concentrically disposed and forming a pivot bearing for said tongue, and a portion of said tongue engaging a portion of said supporting member adjacent said pivot bearing by which cooperative engagement said tongue is held under tension in assembled relation with said supporting member.

2. A belt attachment comprising a supporting member, and a tongue mounted for swinging movement thereon, said tongue and supporting member having curved portions substantially concentrically disposed, and said tongue and member having a co-operating projection and recess by which said tongue is held under tension in assembled relation with said supporting member.

3. A belt attachment comprising a supporting member, and a tongue mounted for swinging movement thereon, said tongue and supporting member having curved portions substantially concentrically disposed, the curved portion of said tongue having a projection at the extreme end thereof, and said supporting member having a recess cooperating with said projection to hold said tongue under tension in assembled relation with said supporting member.

4. A belt attachment comprising a supporting member having a loop portion and a hook portion, a tongue mounted to swing on the loop portion, and means to prevent lateral separation of the parts.

5. A belt attachment comprising a supporting member having a loop portion and a hook portion, a tongue mounted to swing on the loop portion, and means to prevent lateral separation of the parts, said loop portion having a recess, and said tongue being mounted to swing on the loop portion and having a projecting end portion seated in said recess and providing a point of resistance to tension said tongue against swinging movement.

6. A belt attachment comprising a supporting member having a loop portion and a hook portion, said loop portion having a partially cylindrical extension at the outer end thereof and having a recess in an end wall of said loop, and a tongue having a curved end portion partially encircling said cylindrical extension and having an end projection seated under tension in the recess in said loop and providing a point of resistance for said tongue.

7. A belt attachment comprising a supporting member having a loop portion and a hook portion, said loop portion having a partially cylindrical extension at the outer end thereof, and a tongue having a curved end portion partially encircling said cylindrical extension, and means to cover and close the open ends of the cylindrical extension of said supporting member and of the curved end portion of said hoop member.

8. A belt attachment comprising a supporting member, and a tongue mounted for swinging movement thereon, said supporting member being formed of a single piece of sheet metal reversely bent at one end to form a hook and having its other end reversely bent to form a loop portion and having the extreme end of said loop portion projecting through an opening in the middle part of said supporting member and secured in said opening.

9. A belt attachment as set forth in claim 8, in which said supporting member has a partially cylindrical bearing portion for said tongue adjacent but outside of said loop portion and said tongue has a curved end portion loosely concentric with said bearing portion.

In testimony whereof I have hereunto affixed my signature.

JOSEPH H. MONAHAN.
